The schedule referred to in these Letters Patent and making part of the same.

To all whom it may concern:

Be it known that we, Garrettson Smith and Henry Brown, of the City and County of Philadelphia, and State of Pennsylvania, have invented or produced a new and original design for Stoves and we do hereby declare that the following is a full and exact description of the same, reference being had to the accompanying drawings, in which

" 2. " "The Base Plate"

" 3. " "The Side Plate of the Top"

That we claim as our invention and desire to secure by letters patent, is the design and configuration of the moldings and ornaments, as herein described, forming an ornamental design for Stoves.

Witnesses,

W. W.

Garrettson Smith,
Henry Brown,
